ANIMATED MANIKIN

Joseph Albert Morin, Bloomfield, N. J.

Application October 15, 1951, Serial No. 251,304

1 Claim. (Cl. 46—119)

1

This invention relates to an animated manikin. An object of this invention is to provide a manikin which is formed of a hollow body, legs and head, made out of metal, such as aluminum or other light metal, the various elements making up the manikin being formed in complementary half sections which are bolted or otherwise connected together.

Another object of this invention is to provide a manikin wherein one limb such as an arm, is adapted to have movement simulating the movement of the arm of a natural person.

A further object of this invention is to provide a device of this kind wherein the movable element is formed of resilient or flexible material so that the movable element will not be broken if such element should strike a stationary object.

A further object of this invention is to provide in an animated manikin an improved means for effecting movement of the desired limb.

With the above and other objects in view, my invention consists in the arrangement, combination and details of construction disclosed in the drawings and specification, and then more particularly pointed out in the appended claim.

In the drawings:

Figure 1 is a vertical section taken substantially through the center of a manikin constructed according to an embodiment of this invention.

Figure 2 is a fragmentary front elevation partly in section showing the front portion of the manikin removed.

Figure 3 is a fragmentary side elevation of the device.

Figure 4 is a sectional view taken on the line 4—4 of Figure 2.

Figure 5 is a fragmentary sectional view taken on the line 5—5 of Figure 4.

Figure 6 is a fragmentary sectional view taken on the line 6—6 of Figure 3.

Figure 7 is a fragmentary sectional view taken on the line 7—7 of Figure 6.

Figure 8 is a sectional view taken on the line 8—8 of Figure 1.

Figure 9 is a fragmentary sectional view taken on the line 9—9 of Figure 8.

Figure 10 is a sectional view taken on the line 10—10 of Figure 5.

Figure 11 is a fragmentary sectional view taken on the line 11—11 of Figure 10.

Figure 12 is a sectional view taken on the line 12—12 of Figure 1.

Figure 13 is a sectional view taken on the line 13—13 of Figure 7.

Figure 14 is a fragmentary sectional view taken on the line 14—14 of Figure 3.

2

Referring to the drawings the numeral 15 designates generally a hollow body structure which is formed of a torso 16, and the torso 16 is formed of complementary front and back members 17 and 18, respectively.

The torso 16 includes a lower abdomen member 19 formed of complementary front and rear members 20 and 21, and the torso 16 is secured to the abdomen member 19 by means of a plate 10 22 having a pair of longitudinally curved angle members 24 secured thereto, and the front and back members 17 and 18 are secured to the angle members 24 by means of fastening members 25.

15 The abdomen member 19 is formed with an arcuate lower wall 26 which is seated in a concave wall 27 carried by the hollow leg members 28. The hollow leg members 28 are formed with complementary front and rear members 29 and 20 30 which are secured together at their lower ends by bolts 31.

A pair of bolts 32 extend through the plate 22 and the walls 26 and 27 so as to firmly secure the abdomen 19 on the leg structure 28. The torso 16 includes a tubular neck 32, and a hollow head 34 formed with a tubular neck 35 has the neck portion 35 thereof telescoping over the neck 32 and secured thereto by means of a bolt 36.

The feet 37 at the lower ends of the leg structure 30 are adapted to be secured to a supporting member 38 by means of bolts 39. The torso 16 is provided with arms on each side thereof, and one of the arms is movable and is supported and moved as will be hereinafter described. An elongated tubular member 40 extends angularly and downwardly from the upper portion of the side of the torso 16 being formed with a flattened and obtusely disposed upper end 41 which projects loosely through a horizontally elongated opening 40 42 formed in the torso 16. The upper or inner end 41 of the arm member 40 is fixedly secured as by a bolt 43 to an oscillating plate 44 mounted on an upstanding shaft 45.

The shaft 45 is journaled in bearings 46 carried by a horizontally disposed plate or wall 47 fixed in the upper portion of the torso 16 and preferably fixed only to the back member 18. The plate 47 is anchored to the plate 22 by means of a pair of bolts 48, and the lower side of the plate 47 has fixed thereto an electric motor 49. The motor 49 includes a reduction gearing 50 of conventional construction, and a vertically disposed drive shaft 51 extends from the reduction gearing 50 and projects upwardly through the plate 47 spaced from the shaft 45.

55 A crank plate 52 is fixed to the shaft 51 on the

upper side of the plate 47, and the plate 52 has pivotally mounted thereon a crank pin 53. The crank pin 53 includes a right angularly disposed threaded shaft 54 which provides one means for connecting the crank pin 53 with the plate 44.

An eccentrically disposed pin 55 is rockably carried by the plate 44 and includes a right angularly disposed threaded shaft or rod 56. A tubular connecting member or link 57 is threaded on the two shafts or rods 54 and 56, and preferably the shafts 54 and 56 are provided with right and left hand threads, respectively. The opposite ends of the connecting member 57 are split as indicated at 58 in Figure 11, and the clamping band 59 engages about the split portion of the connecting member 57 so as to tightly hold connecting member 57 against movement relative to the threaded shafts 54 and 56.

The arm 40 has fixed on the outer lower end thereof a right angularly disposed plate 60, and a pair of bushings 61 are secured in spaced relation to each other on the forward or lower side of plate 60 by fastening means 62. The arm 40 constitutes the upper arm, and a forearm 63 is rockably mounted in the bushings 61 and extends downwardly therefrom.

The forearm 63 includes a resilient elongated member 64 preferably formed of rubber or the like which is clamped as by clamping bands 65 to a bar 66. The forearm 64 has projecting from the forward end thereof a plurality of wires 67 which are five in number and are adapted to be embedded in a hand which is also formed of rubber or resilient material capable of being bent.

The wires 67 provide a means whereby the fingers or hand may be bent and retained in their bent position. In this manner the hand may be partially or completely closed and made to grasp an article which is to be swung back and forth with the swinging of the forearm 64 and the upper arm 40.

The bar 66 is tubular and is threaded onto a threaded stud 68 which is carried by a right angularly disposed member 69 having studs 70 journaled in the bushings 61. In order to provide a means whereby the forearm 63 will have movement relative to the upper arm 40, I have provided a joint tie rod generally designated as 71.

The tie rod 71 includes a rubber tubular intermediate member 72 which at its inner end telescopes over a jointed bar 73 having a pair of universal joints 74 and 75 interposed therein whereby the arm 63 may yield either vertically or horizontally upon impacting an extraneous object, the two universal joints enhancing the flexibility of the structure. The intermediate member 72 is adjustably clamped to the bar 73 by means of a clamping band 76.

The inner end of the bar 73 indicated by the numeral 77 is fixed to a bracket 78 having a longitudinally bent extension 79 formed with an elongated slot 80. Fastening members 81 extend through the slot 80 so that the bracket 78 may be horizontally adjusted to provide for the desired swinging movement of the forearm 63 relative to

the upper arm 40. The forward end of the rubber tube 72 is connected to a jointed bar 82 by means of a clamping band 83, and the bar 82 has extending from the forward end thereof an angled connector 84 which pivotally engages through the tubular member 66.

The bracket base member 79 is also tightly held to the side of the back member 18 by means of a strap 85 which is secured to the back member 18 across the base member 79 by fastening members 86.

In the use and operation of this manikin the motor 49 is connected to a source of electric current supply, and upon rotation of the crank or cam plate 52 plate 44 will be oscillated back and forth so as to thereby oscillate or swing arm members 40 and 63. Inasmuch as the tie rod 71 is of shorter length than the upper arm 40 as upper arm 40 swings back and forth tie rod 71 will also cause a swinging of the forearm 63 relative to the upper arm 40.

While in Figure 6 the forearm 63 is shown as being in substantial alignment with the upper arm 40 in the forward position of the forearm 40, it will be understood that adjustment of the length of the tie rod 71 will provide for initial angular position of the forearm 63 in the forward position of the latter.

The forward and rear position of the arm structure in the swinging movement thereof can be adjusted by lengthening or shortening the connection between the crank pins 53 and 55 through the adjustable linkage 57.

This device may be made out of metal or other suitable material and may have the usual garments disposed thereon which will cover up the arm mechanism so that the device will more closely simulate a person.

What is claimed is:

40 An animated manikin comprising a hollow upstanding body formed of complementary front and rear sections, a horizontal wall disposed in the upper portion of said body, an arm member, means carried by said wall swingably supporting said arm member, a rotatable crank plate carried by said wall, a crank pin carried by said crank plate, and a linkage connected between said crank pin and said arm, said arm comprising pivotally connected together upper and lower arm members, means for rotating said crank plate to swing said upper arm member, and a tie member, including a plurality of spaced universal joints pivotally connected between said body and said lower arm member to permit yielding of said lower arm member upon impacting an extraneous object.

JOSEPH ALBERT MORIN.
